AUTOMATIC CONTRIVANCE FOR RECEIVING WRITTEN MESSAGES BY TELEPHONE

Filed Nov. 17, 1928

INVENTOR
Otto Watzka
BY C. P. Goepel
his ATTORNEY

UNITED STATES PATENT OFFICE

OTTO WATZKA, OF VIENNA, AUSTRIA, ASSIGNOR TO CHARLES S. BLEICHER, OF NEW YORK, N. Y.

AUTOMATIC CONTRIVANCE FOR RECEIVING WRITTEN MESSAGES BY TELEPHONE

Application filed November 17, 1928, Serial No. 320,026, and in Austria April 21, 1928.

This invention relates to the reception of messages by telephone, particularly messages in written form when the party called is absent.

5 An object of the invention is to provide an arrangement of apparatus and circuits which can be utilized in combination with ordinary telephone circuits and instruments to enable the party calling to ascertain, first that the 10 party called is not present at the opposite end of the line; and then by the manipulation in a predetermined manner of the well-known dial for automatic telephones, to cause the message to be written down at the place 15 called, to be kept till the party called returns.

It is accordingly characteristic of this invention, that, after a normal connection is obtained, the mechanism of this apparatus, which may be worked either mechanically or 20 electrically, is set in motion through the continuance of the operation of the dial which must continue as the message is transcribed. The apparatus can also be used where there 25 are no automatic telephones, but, in such cases the caller's telephone apparatus must have a dial, if he desires to send such telephonic written messages.

The other objects and advantages of the 30 invention are set forth in the following description, taken with the accompanying drawings by which a form of my invention and the method of proceeding, are illustrated. I do not, however, wish to be limited to the 35 details shown herein, as I may vary the arrangement without departing from the principle of the invention or exceeding the scope of the appended claims.

On the drawings,

Figure 1 is a side elevation of part of the 40 mechanism of my invention, for recording a telephone message in writing;

Fig. 2 is a top plan of what appears in Fig. 1;

Fig. 3 shows the controlling circuits for 45 sending and producing the writing of a message; and

Fig. 4 shows a modification of such circuits.

The same characters of reference indicate 50 the same parts throughout.

In practice the telephonic writer of this invention contemplates the employment of a so-called Strowger switch, generally used in automatic telephones, mounted to move in both a rotary and an axial direction. These 55 movements are obtained by energizing a pair of magnets. After a letter has been written, a circuit is closed through a releasing magnet, and the rotary member or body of the switch is returned to its original position. 60

The writing of one letter is thus effected through the Strowger switch. When the body of the switch is mounted on a vertical axis, the body is lifted and turned to make the writing. Figures 1 and 2 show the lifting magnet "H", the turning magnet "D" 65 and the release-magnet "A".

As distinguished, however, from the usual Strowger switch, no contact track is employed thereby eliminating contact forks. 70 Instead a body or drum "Tr" (Figure 1) bearing figures, letters and signs in type-form on its circumference, is fastened on the rotary spindle "a" carrying the drum.

According to this invention the member or 75 drum "Tr" is set in motion when the caller uses the telephone dial to close and open the calling circuit and create impulses of current. These impulses are sent through the feed-relay "Sp1" (Figure 3) to the circuit 80 of the writing apparatus of the called telephone instrument. At the first series of impulses the drum "Tr" is lifted, at the second series it is turned. It is, therefore, necessary to send two series of impulses for the writing 85 of a letter. The body "Tr" of the Strowger switch can make ten vertical and ten horizontal steps. It is, therefore, possible to write one hundred letters, figures or signs.

Through the lifting and turning of the 90 drum the desired letter gets into typing position. That is, it comes opposite an inking ribbon "Fb", mounted to move as in an ordinary typewriter, and in front of this ribbon there is a pivoted striking lever "Th" between which and the ribbon "Fb" a paper strip or band "Pst" passes. When the lever "Th" is actuated to strike the ribbon and the paper, it presses them against the drum and the letter, resting in typing position, is print- 95 100

ed on the paper band. After this the drum is to be returned to its original position. At this instant the release-magnet "A" is energized, and lifts the retaining pawl or catch 5 "Sz1" of the horizontal cog wheel or ratchet "Zr", as well as the pawl "Sz2" of the round rack on the spindle "a". Then the drum is thus liberated and is turned back by a spring; also it drops by gravity against a rest "As". 10 Starting position is thus regained.

At the first upward step of the drum the longer of a pair of spring contacts "h", which is pressed down by the drum, is freed, so that the contact of the two springs takes place. At 15 the return of the drum against stop "As", the two springs separate. In the same manner the longer of two spring contacts "d" is moved at the first turning movement of the drum to make contact with the other. The 20 end of this longer spring is received in a vertical groove or recess "n" in the side of the member "Tr", when the latter is in starting position, as shown in the description of the switch. Both pairs of contacts "h" and "d" 25 are needed for the control of certain relays, as will be later set forth herein.

Figure 3 shows diagrammatically the circuits for supplying both parties with power, in connection with the switch of the automatic contrivance for receiving telephonic 30 written messages. On this view the individual relays are marked with capital letters, and the contacts thereof with the same small letters. The contacts are all shown in dead 35 relay position.

The two switch contacts "Ki1" and "Ki2" of the called subscriber "Tn2" are in center position, so that it is possible to receive incoming calls. Should, however, the subscriber "Tn2" leave his room, he throws the switch arm to open the contacts "Ki1" and "Ki2" so that his telephone apparatus is thus immediately connected with the telephonic writer. An incoming call will therefore set 40 the relay "X" of the writing apparatus into operation said relay acting in a supervisory capacity for the several operating relays included in the apparatus. The circuit is by way of the usual grounded battery and winding 45 of a feed relay to connecting wire "1", closed contact "Sr7", connecting wire "2", i. e. the connecting wire of the central office to the called telephone subscriber, open switch contact "Ki1", connecting wire "3", relay "X" 50 of the telephonic writer, connecting wire "4", contact "v1", ground. Relay "X" is thus actuated and moves switch contact "x1". The winding "1" of the humming switch relay "E" is thus actuated through a circuit comprising minus pole nearest to contact "x1", 55 switched contact "x1", connecting wire "5", contact "v2" of the not yet live relay "V" connecting wire "6", winding "1" of the humming switch relay "E", plus pole connected 60 to the other terminal of this winding.

This relay "E" immediately brings its winding "II" into play. The circuit here is from the plus pole adjacent contact "W1", through contact "W1" of the not yet closed relay "W", connecting wire "7", winding "II" of the 70 humming switch relay "E", connecting wire "8", switched contact "e1" and minus pole, adjacent this last-named contact. The called relay "E" then switches in the winding "I" of the humming relay "S"; and a circuit is established from the plus pole at the left of relay "S", winding "I" of the humming relay "S", connecting wire "9", contact "s1" of the 80 humming relay, connecting wire "8", contact "e1", and minus pole at "e1". The humming relay is switched, but in the next moment disconnected, because the circuit of contact "s1" is broken. This relay is now dead, but, in the next moment alive again, then it is dead again, and alive, etc. The successive 85 actuations of this relay causes vibrations, and these vibrations give rise to cause a humming tone, which is inductively sent in an audible way to the calling subscriber over winding "II" of the humming relay in a single pole 90 manner. The circuit is by way of ground, winding "II" of the humming relay "S", wire connection "10", condenser "C", wire connection "11", switch contact "e2" of the switched 95 relay "E", wire connection "3", open switch contact "Ki1", wire connection "2" to the calling subscriber.

Through the connection of relay "X" the relay "V" also becomes alive, the circuit being from minus pole adjacent contact "x1", this 100 switched contact "x1", wire connection "5", relay "V" and plus pole thereat. This relay has a copper cylinder, therefore answering slower, and will keep its contacts switched on even if the circuit should temporarily be broken. During the message relay "V" remains 105 alive continuously. Contact "v2" disconnects winding "I" of the humming switch relay "E", which latter remains alive over its winding "II", at the same time the switch 110 contact "v1" switches relay "X" uninterrupted from grounded pole to the called subscriber's wire. Relay "X" then has its circuit as follows: grounded battery, winding "II" of feed relay "Sp2", wire connection 115 "1", contact "sp1", wire connection "2", open switch contact "Ki1", wire connection "3", relay "X", wire connection "4", switched contact "v1", wire connection "12", open switch contact "Ki2", wire connection "13", winding "I" of feed relay "sp2", ground. 120

The humming sound, audible to the caller, was his signal that the person called has the telephonic writing contrivance on his telephone apparatus, but is absent. The caller 125 can then start writing the message. For every letter, written in that manner, two numerals are to be dialed. As, for example, for letter "a" the number "23" is first dialed. During the return of the calling 130

device to the normal position two interruptions of the circuit are caused. This individual feed relay "Sp1" drops off twice at the central office, and through that sets contact "Sr1" in motion, at the same time interrupting just as often the circuit of relay "X" of the telephonic writer. The relay "X" will fall off synchronously just as often. Therefore contact "x1" will switch over as often as the interruptions will occur at the caller.

With the first falling off of relay "X", the delayed relay "W" is switched in; the circuit being from minus pole at contact "w1", this contact, wire connection "14", contact "w3" of the switched relay "V", wire connection "15", relay "W" and plus pole at same. This relay "W" remains connected during a series of impulses, after which it falls off again. With the actuation of relay "W" the winding "II" of the humming switch relay is disconnected from the minus pole through its contact "w1". The relay "E" then falls off. Through that the humming relay falls off too. The humming is thus at an end.

At the first series of impulses the magnet "H" is energized with every actuation of the relay "X". The circuit is from minus pole at contact "w1", this contact wire connection "5", contact "w2" of the delayed relay "W", wire connection "16", contact "st1" of the not yet closed steer relay "St", wire connection "17", lift-magnet "H", and plus pole of same. Every time the lift-magnet "H" is energized the drum "Tr" rises a step, because the lever "Ha" engages a tooth of the round rack "Zst" and lifts it one step higher. See Figure 1. The latch "Sz2" prevents dropping. The drum makes for the latter "a", for example, two upward steps. With the first step the contact "h" comes together because the long spring of this pair is released through the rising drum, from its depressed position.

At the end of the first impulse series the relay "W" drops off, because the circuit is interrupted. The dropping off of this relay energizes the steer or selector relay "St" by a circuit through minus pole at contact "w3" of the not yet active relay "W", this contact "w3", wire connection "16", steer relay "St", wire connection "17", contact "t1", wire connection "18", switched contact "h" of the lift pack and plus pole thereat. Contact "st2" of steer relay "St" disconnects the winding of the release magnet "A" from adjacent minus pole. Furthermore the circuit of the impulses is changed through contact "st1" from the magnet "H" to the magnet "D".

As soon as the subscriber "Tn1" proceeds to send the second series of impulses, as for example, writing the second figure "3" for letter "a", the delayed falling-off relay "W" is actuated, if relay "X" drops off. Relay

"W" would interrupt the circuit in which the delayed dropping-off steer relay "St" is, if it were not for the following supporting circuit: minus pole at contact "st2", this contact of switched relay "St", wire connection "19" contact "v4" of switched relay "V", wire connection "16", relay "St", contact "t1" of not yet switched relay "T", wire connection "18", switched contact "h" and plus pole at same. At every actuation of relay "X" the magnet "D" therefore becomes alive through a circuit embracing minus pole at contact "w1", this contact, wire connection "5", contact "w2" of switched relay "W", wire connection "16", contact "st1" of switched relay "St", wire connection "20", turnmagnet "D" and the adjacent plus pole. At every actuation of the magnet "D" the drum "Tr" makes a horizontal step, because the lever "Da" moves the cog wheel "Zr" against the force of a spring "R/d" which is coiled round the spindle "a" and regulates the horizontal return of the drum. The dog "Sz1" always holds the drum in the assumed position. Upon the first horizontal movement of rotation the long spring of the pair "d" is forced out from the vertical groove "N" of the drum, and thus, the two contacts are caused to engage. The relay "P" becomes alive during the second series of impulses through the circuit of plus pole at "d", the two contacts "d", wire connection "21", switched contact "st3", wire connection "22", switched contact "w4", wire connection "23", relay "P", and minus pole at same. The relay "P" is built as a transfer switch relay, as often used in automatic telephony. Its lever has a transfer spring which moves a cog wheel (not shown) if relay is alive. On the axle of the cog wheel is a ribbed transport cylinder, against which a second cylinder presses. Between the two cylinders (not shown) the paper band "Fb" passes and moves forward through the turning of the transport cylinders.

After the second series of impulses the delayed relay "W" drops off again. Then the relay "P" drops off too; the dialing of the desired letter is finished, and the drum is in dialing position. The type relay "T" is now switched in from plus pole at "D", the contacts "d", wire connection "21", switched in contact "st3", wire connection "22", contact "w4" of not yet switched relay "W", wire connection "24", type relay "T", to the adjacent minus pole. The lever of this relay "Ta" comes into action and presses the paper band "Fst" against the color ribbon "Fb" and both against the set letter of the drum. Thus the imprint of the letter is made on the paper band.

Through the relay "T" is contact "t1" (Figure 2) which becomes active and interrupts the circuit of the steer relay "St". But the opening of this relay is delayed. Its contact

"st3" interrupts the circuit of the type relay and causes the type relay to drop at once its type bar or lever "Th". This is returned through the elasticity of a suitable spring to 5 its normal position.

Contact "st2" of the dropped off relay "St" now establishes a circuit containing the release magnet "A" of the Sfrowger switch, to wit, minus pole at "st2", this contact "st2" 10 of the not yet switched steer relay "St", wire connection "25", winding of release magnet "A", wire connection "21", switched contact "d", to the plus pole at same.

As soon as the release magnet is active, 15 the dogs "Sz1" and "Sz2" are lifted (Figure 1). Through the influence of the return spring "Rfd" the drum is turned back and drops off by its own weight to normal position. With that, the contacts "h" and "d" 20 are brought back to normal and the circuit of the release magnet is interrupted.

The dialing of the next letter can now begin. The procedure takes as little time as the dialing of the calling subscriber "Tn1".

25 At the end of the dialing, or, when the calling subscriber is finished with writing, he hangs up his receiver; and the feed relay "Sp1" drops off permanently, and with it the relay "X". The relay "W" is then switched 30 in the same way as before. Right afterward the relay "V" drops off. Now a live condition of relay "W" and a dead condition of relay "V" exists. At this moment relay "P" gets an impulse through the circuit of the 35 plus pole at "W1", contact "w1" of switched relay "W", wire connection "26", contact "v5" of not switched relay "V", wire connection "23", relay "P" and minus pole at this point. Now the paper band is moved one 40 step further, making a space in the written message, even if the calling subscriber has forgotten to indicate that after finishing his written message. Since the paper band moves one step further, before the next letter of an 45 other message is written, the space between the finished message and the first letter of the next message is therefore double.

Contact "v6" switches release magnet "A", if the calling subscriber should hang up receiver after having dialed but once. Thus 50 a circuit is created in which the release magnet "A" lies as follows: plus pole at "H", switched contact "h", wire connection "18", contact "v6" of not switched-in relay "V", 55 wire connection "21", winding of release magnet "A", wire connection "25", contact "st2", and adjacent minus pole.

In cases where an alphabet of 10 letters or 60 figures will suffice, the writing of every letter will be done by single dialing of the calling device. In that case a code could be used.

Then effects are produced of such nature 65 that the current impulses are given to a transport relay "D" (Figure 3) which is built as

transfer relay. The lever "a" turns a small type cylinder or wheel "Tr". On the surface of the cylinder are the letters. At the first step, figured from normal position, a spring of a pair "d" is lifted from a groove "n" of type wheel. At the proper time, the type relay "T" is switched in, the same manner as described before. Its armature lever becomes active, and presses the type fork "Th" with the paper band against color ribbon "Fb", against the type wheel and selected letter. Afterwards the release magnet "A", which lifts the dog "Sz", is switched. But, with that the type wheel, through its return spring, is turned back to starting point. The transmission of the paper band is in the same manner as described before.

The active relay "X", switching, transferring and switching off humming sound, takes place in the same manner as shown in the description of Figure 2. The same circuits are used for the switching of the relays "V" and "W".

The difference here is that the impulse series are not switched to lifting and turning magnets, but to a magnet turning only, and one impulse series is sufficient for the writing of a sign on the receiving contrivance.

At every actuation of relay "X" during an impulse series, a circuit is made which switches the transport relay "D" through the circuit of minus pole at "w1", contact "w1" of impulse relay "X", wire connection "5", contact "w2" of relay "W", which is switched in during every series of impulses, wire connection "27" transport relay "B", plus pole thereof, as in Figure 4. The transport relay "D" puts its lever "a" (Figure 3) into action at every step, and moves a cogwheel "Zr" as used in automatic telephones for transfer relays. On the shaft of this cogwheel is the type wheel "Tr", on which the letters and figures are placed. A dog "Sz" makes the return of type wheel impossible by the return spring "Rfd", until the wheel is released.

At the first step, figures from the starting point, marked by a stop "As", the longer spring of pair "d" is lifted from a groove "n" of type wheel and the two spring contacts are made to engage.

During a series of impulses a circuit (Figure 4) is made with that in which relay "P" lies through plus pole at "D", switched contact "d", wire connection "28", contact "t1" of not yet switched relay "T", wire connection "29", relay "P", wire connection "30", contact "w1" of relay "W", which is switched during an impulse series at minus pole at this point.

The functions and construction of relay "P" are the same as the relay of Figure 2. It moves the paper band "Pst". It remains energized on account of its own contact "p1", 130

110

115

120

125

through the circuit of minus pole at "p1", contact "p1", wire connection "30", relay "P", wire connection "29", contact "t1", wire connection "28", contact "d" and plus pole at same. See Figure 4.

5 At the end of the series of impulses, the selected letter is in typing position. The type relay "T", Figure 4, which has the same functions as in Figures 1 and 2, is switched in by the circuit of minus pole at "w1", contact "w1" of relay "W", which drops off after the series of impulses, wire connection "31", contact "p2" of switched relay "P", wire connection "32", contact "a1" of not yet 10 switched in release magnet "A", wire connection "33", type relay "T", and plus pole of the latter.

15 The imprint of the selected letter is made in the same manner as before, through the 20 switching in of the type relay "T".

25 The switched-in type relay "T" sets in contact "t1" in action, which interrupts circuit where relay "P" lies. Relay "P" drops off and switches release magnet "A" in through "h", the plus pole and switched-in contact "d", wire connection "28", release magnet "A", wire connection "34", contact "p2" of delayed relay "P", wire connection "31" contact "w1" of not switched-in relay "W", minus pole of same, as shown on Figure 4.

30 The active release lifts its dog "Sz" (Figure 2) by which the type wheel "Tr" through the return spring "Rfd" is thrown back into normal position, marked by a stop "As". In 35 this position the longer spring of pair "d" snaps back in the groove "n" of type wheel and interrupts the circuit of the release magnet "A".

35 The dialing of the next sign can begin now. 40 Since the above described functions are synchronous with runback of the calling device, the calling subscriber need not wait between the dialing of one letter or the other. The paper band moves on automatically at the 45 end of the written message, when the receiver is hung up. This is caused by relays "V" and "W", the same as described in connection with Figure 2. The circuit for switching relay "P" at the conclusion of the message is as follows on Figure 4, from plus pole at "w3", contact "w3" of relay "W", which is temporarily active at conclusion of the message, wire connection "35" contact "v4" of relay "V", which is dead at conclusion of the message, wire connection "28", contact "t1" of not switched-in type relay "T", wire connection "29", relay "P", wire connection "30", contact "w1" of relay "W", which is temporarily switched at conclusion of the message, and adjacent minus pole.

60 I claim:

1. In a telephone system, a calling station including means for transmitting electrical impulses, a called station including means for recording said impulses, means asso-

ciated with the recording apparatus for signaling the calling station that the recording apparatus is operatively connected to the system including a make and break relay circuit, and means for superimposing the electric impulses arising from the making and breaking of said relay circuit on the line of the calling station.

2. In a telephone system, a calling station including means for transmitting electrical impulses, a called station including means for recording said impulses, means associated with the recording apparatus for signaling the calling station that the recording apparatus is operatively connected to the system including a make and break relay circuit, and means for superimposing the electric impulses arising from the making and breaking of said relay circuit on the line of the calling station, including a relay circuit normally connected to ground and operatively connected with the make and break relay circuit, and switch means controlled by said relay circuit for connecting the relay directly to the line.

3. In a telephone system, a calling station including means for transmitting electrical impulses, a called station including means for recording said impulses, means for signaling the calling station that the recording apparatus is operatively associated with the line, a supervisory relay responsive to an incoming call for operatively connecting the signaling means to the line, and switch means controlled by said relay for disconnecting the signal means from the line and directing incoming impulses to the recording apparatus.

4. In a telephone system, a calling station including means for transmitting electrical impulses, a called station including means for recording said impulses, means for signaling the calling station that the recording apparatus is operatively associated with the line, a supervisory relay responsive to an incoming call for operatively connecting the signaling means to the line, and switch means controlled by said relay for disconnecting the signal means from the line and directing incoming impulses to the recording apparatus, said supervisory relay being arranged to maintain the signal circuit associated with the line until the continuity of the calling line is broken.

5. In a telephone system, a calling station including means for transmitting periodic electrical impulses, a called station including means for recording said impulses, said recording means including a type bearing member mounted for axial and rotary movements, a supervisory relay controlling said recording apparatus and responsive to incoming impulses, a magnet for moving the type bearing member axially, and a magnet for rotating the type bearing member, and a selector relay for successively energizing

70

said magnets in response to incoming signals whereby the type bearing member is first moved axially and then rotated into a predetermined position.

5. In a telephone system, a calling station including means for transmitting periodic electrical impulses, a called station including means for recording said impulses, said recording means including a type bearing member mounted for axial and rotary movements, a supervisory relay controlling said recording apparatus and responsive to incoming impulses, a magnet for moving the type bearing member axially, and a magnet 10 for rotating the type bearing member, and a delayed action selector relay for successively energizing said magnets, said relay arranged to maintain the first mentioned magnet energized during the reception of a group of electrical impulses, and the second mentioned magnet during reception of a succeeding group of impulses, and switch means controlled by said supervisory relay for returning said selector relay to normal position 15 at the expiration of said second group of electrical impulses.

7. In a telephone system, a calling station including means for transmitting electrical impulses, a called station including means 30 for recording said impulses, said recording means including a type bearing member movable axially and rotarily in successive stages to a selected recording position in response to successive groups of transmitted signals, 35 electromagnets for so moving the type bearing member, a supervisory relay for controlling said electromagnets, a slow acting relay energized through the supervisory relay at the first impulse received and designed 40 to "hold" during reception of an uninterrupted group of impulses and then "fall off," switch means closed by said slow acting relay for completing a circuit through the electromagnet operating to move the type bearing member through its first stage of movements, 45 a relay energized by the falling off of the slow acting relay and operating to energize the electromagnet for moving the type bearing member through its second stage of movements upon reception of a second group of 50 electrical impulses, and means for holding said last mentioned relay energized when said slow acting relay picks up due to the reception of the second group of impulses.

8. In a telephone system, a calling station, a called station including means for recording electrical impulses transmitted over the system, said means including a type bearing member movable axially and rotarily in successive stages to a selected recording position, a record strip and means for recording a selected type thereon and means for advancing said record strip with respect to the type bearing member to properly space the successive type records, said last mentioned

means including a control circuit and means operative in response to the initial rotary movement of the type bearing member for completing said circuit.

9. In a telephone system, means for recording electric impulses transmitted over said system, including a type bearing member, means responsive to transmitted impulses for moving said member to a selected position, releasable means for holding said member in such position, a record sheet for receiving an imprint of a selected type, means for imprinting the type thereon, and means actuated in response to actuation of the imprinting means for actuating the type bearing member release means. 70

10. In a telephone system, means for recording impulses transmitted over said system including a type bearing member movable axially and rotarily in successive stages 85 to select a predetermined type, means responsive to said impulses for so moving the type member, means for recording a selected type including a record sheet, and means for imprinting the selected type thereon, and means 90 controlled by rotary movement of the type bearing member for advancing the sheet before an imprint is made thereon.

11. In a telephone system, a calling station including means for transmitting electric impulses, a called station, and means for recording the transmitted impulses including a type bearing member movable to a selected type recording position, means responsive to transmitted impulses for so moving the member, means for recording a selected type including a record sheet and means for advancing the sheet with respect to the type bearing member, said last mentioned means being responsive to cutting off of the calling 105 station.

12. In a telephone system, a calling station including means for transmitting electrical impulses, a called station and means for recording transmitted impulses including 110 a type bearing member movable axially and rotarily in successive stages to select a predetermined type to be recorded, means for recording said type including a record sheet, and means for periodically advancing said 115 sheet with respect to the type bearing member, said last mentioned means being responsive to the initial rotary movement of the type bearing member and cutting off of the calling station.

13. In a telephone system, a calling station including means for transmitting electrical impulses, a called station and means associated therewith for recording said impulses, the recording means including a type bearing 125 member movable axially and rotarily to a selected position, means for so moving the type bearing member including a magnet for imparting axial movement thereto and a magnet for imparting rotary movement 130

- thereto, relays for controlling said magnets including a supervisory relay responsive to incoming impulses, a selector relay, and a slow acting relay interposed between the supervisory relay and said selector relay, circuit connections between said relays, the circuit of the selector relay including a normally open switch controlled by initial axial movement of the type bearing member, said slow acting relay being energized through the supervisory relay upon reception of an electrical impulse and designed to "hold" throughout the reception of an uninterrupted group of impulses and then "fall off", circuit means for energizing the magnet for axially moving the type bearing member by said first group of impulses, means for energizing the selector relay by falling off of the slow acting relay, the normally open switch of the selector relay circuit being closed by initial axial movement of the type bearing member, said selector relay energizing the magnet for imparting rotary movement to the type bearing member through a succeeding group of uninterrupted impulses, and means for printing the selected type.
14. In a telephone system a calling station including means for transmitting electrical impulses, a called station including means for recording said impulses and signal means for indicating to the calling station that the recording apparatus is connected to the line, and a supervisory relay responsive to an incoming coil to successively connect the signaling means and said recording apparatus to said calling line.
15. In a telephone system a calling station including means for transmitting periodic electrical impulses, a called station including means for recording said impulses, said recording means including a type bearing member mounted for axial and rotary movements, electromagnetic means for axially moving the type bearing member, electromagnetic means for rotating said type bearing member, a supervisory relay for controlling said electromagnetic means, and for initially transmitting incoming signal impulses to one of said electromagnetic means, a slow acting relay energized through said supervisory relay and functioning to "hold" through the first group of signal impulses, a selector relay energized by the "falling off" of said slow acting relay and connecting said second mentioned electromagnetic means to said incoming signals whereby to selectively move the type bearing member to a predetermined recording position.
16. In a telephone system, a calling station including means for transmitting periodic electrical impulses, a called station including means for recording said impulses, said recording means including a type bearing member mounted for axial and rotary movements, a lock for maintaining said type bearing member in a predetermined axial position to which it may be moved, separate electromagnetic means for selectively moving the type bearing member axially and rotationally, a selector relay for selectively energizing said electromagnetic means, a supervisory relay for controlling said selector relay and electromagnetic means energized in response to axial movement of the type bearing member to actuate the locking means to maintain said member in said axial position.
17. In a telephone system, a calling station including means for transmitting periodic electrical impulses, a called station including means for recording said impulses, said recording means including a type bearing member mounted for axial and rotary movements, a supervisory relay controlling said recording apparatus and responsive to incoming impulses, a magnet for moving the type bearing member axially, and a magnet for rotating the type bearing member, a delayed action relay for initially transmitting signal impulses to said first mentioned magnet to move the type bearing member axially, a selector relay normally deenergized and having its energized circuit partially set up by the initial axial movement of the type bearing member and completed by the falling off of said slow acting relay at the end of a group of signal impulses, said selector relay being thus energized to transmit the following series of electrical impulses to said second mentioned magnet to rotate the type bearing member.
18. In a telephone system, a calling station including means for transmitting periodic electrical impulses, a called station including means for recording said impulses, said recording means including a type bearing member mounted for axial and rotary movements, a supervisory relay controlling said recording apparatus and responsive to incoming impulses, a magnet for moving the type bearing member axially, and a magnet for rotating the type bearing member, a delayed action relay for initially transmitting signal impulses to said first mentioned magnet to move the type bearing member axially, a selector relay normally deenergized and having its energized circuit partially set up by the initial axial movement of the type bearing member and completed by the falling off of said slow acting relay at the end of a group of signal impulses, said selector relay being thus energized to transmit the following series of electrical impulses to said second mentioned magnet to rotate the type bearing member, circuit means for again energizing the delayed action relay by a second group of electrical impulses, a record sheet associated with the type bearing member and electromagnetic means for advancing the same, said magnet being normally deenergized, means for partially completing the circuit of said

last mentioned magnet by the initial rotary movement of the type bearing member, and means for completing the circuit through said last mentioned magnet by the falling off of the slow acting relay at the end of said second group of signal impulses.

In testimony that I claim the foregoing as my invention, I have signed my name hereto.
